UNITED STATES PATENT OFFICE.

MICHAEL CROUGH, OF ILLION, NEW YORK.

SAFETY-RAZOR-BLADE HOLDER.

Application filed May 3, 1923. Serial No. 636,453.

To all whom it may concern:

Be it known that I, MICHAEL CROUGH, a citizen of the United States, residing at Ilion, in the county of Herkimer and State 5 of New York, have invented new and useful Improvements in Safety-Razor-Blade Holders, of which the following is a specification.

This invention relates generally to improvements in safety razors, and particularly to improvements in safety razor blade 10 holders.

One object of the invention is to provide a holder having a tang portion and a handle, 15 simulating, in general, the appearance and structure of an ordinary non-safety or old style razor and which allows a person to shave, and a blade held in the holder to be resharpened, honed or stropped, with all 20 the ease and conveniences afforded by the old style razor.

Another object of the invention is to provide a holder which is adapted to hold and thereby permit of the use of safety razor 25 blades of any of the forms in general use, according to the fancy of the user or as circumstances may require.

Still another object of the invention is to provide a safety blade holder which will 30 firmly and securely hold a blade in position, which is adapted for the ready and convenient application and removal of a blade, and which is also compact in form, and susceptible of being easily manipulated 35 and of being manufactured and sold at a comparatively low cost.

The invention consists of the features of construction, combination and arrangement 40 of parts, hereinafter fully described and claimed, reference being had to the accompanying drawing, in which:—

Figure 1 is a perspective view of a safety blade holder embodying my invention, showing a blade clamped therein.

Figure 2 is a central longitudinal section through the same.

Figure 3 is an end elevation.

Figure 4 is a cross-section on the line 4—4 of Figure 2.

Figure 5 is a cross-section on the line 5—5 of Figure 2.

Figure 6 is a cross-section showing the mode of applying a certain form of blade to the holder.

Figure 7 is a similar view showing the blade clamped therein.

In the practical embodiment of my invention I provide a safety blade holder comprising a holder portion proper 1, a tang portion 2, and a handle 3, simulating in general the appearance of an old style razor. 60

The holder portion 1 consists of a pair of clamping plates 4 and 5, which are similar in form and construction to each other. Each plate comprises a body portion 6 having at its rear or back edge an outturned longitudinally extending flange 7 and having at a point adjacent to but in rear of its front edge an inwardly offset portion 8. The portions 8 dispose the front portions 70 9 of the plates closer to each other than the body portions 6, and these portions 9 are provided with inner blade clamping faces 10, which are parallel with the inner faces of the body portions of the plates, and outer beveled faces 11 which converge in the direction toward the front edges of the plates. As shown, the tang portion 2 is composed of strips projecting from the inner ends of the plates and which have their outer ends arranged to straddle the handle 3 and which are pivoted thereto by a pin or rivet 12. This pin or rivet 12 passes through registering openings in the handle and tang strips and has at one end a tapered head 13 fitted in a correspondingly shaped countersink portion of the opening in one of the tang strips and is formed at its opposite end with a circular head 14 loosely fitted in the opening in the other tang strip. 80

This mode of connection allows the second-named tang strip to slide and to rock or oscillate on the circular rivet head, thus adapting the tang strips to accommodate themselves to certain rocking motions of the plates 4 and 5, as hereinafter described. 90

The plates 4 and 5 are loosely joined adjacent to their ends, by headed pins or rivets 15, passing loosely through openings 16 therein. These pins are spaced a sufficient distance apart to permit a safety razor blade of any length used to be disposed between the pins and in the space between the plates 4 and 5. The pins are arranged in line with the inner ends of V-shaped portions 17 stamped inwardly from the body portions of the plates and have their heads seated in the channels or grooves formed in the outer faces of the plates by the corresponding depressions. The vertices of these pairs of V-shaped portions at opposite ends of the plates abut and normally space the 100 105 110

plates a predetermined distance apart along a substantially central longitudinal line. Said portions 17 also provide trunnions on which the plates are adapted to be rocked or tilted along such line as an axis of motion. As the pins 15 loosely connect the plates such motion is permitted to adapt the portions of the plates above and below the line of the rivets to rock or tilt in opposite directions, so that in one direction of rocking motion of the plates the jaws or clamping portions 10 will close or move inwardly towards each other, while in the opposite direction of movement of the plates the jaws 10 will open or move outwardly and away from each other. The described pivotal connection between the tang strips and handle adapts said strips to rock with the plates without disconnection from the handle, as the extent of spreading action of the tang strips will not be greater than that allowed by the pins 15.

Pivots mounted upon pins 18, loosely engaging openings in the plates 4 and 5, are locking wedges 19, arranged adjacent to the ends of said plates so as to be swung into the space between the plates or outwardly beyond the ends of the plates. These wedges have milled gripping surfaces 20 for engagement by the thumbs or fingers of the operator, whereby said wedges may be manipulated. The surfaces 20 are so disposed as to project above the flanges 7, when the wedges are in locking position, so as to enable the wedges to be forced tightly into such position as well as to be swung vertically for a releasing or unlocking action.

Figure 3 of the drawing shows the parts of the holder when in position to clamp a razor blade, and Figure 4 shows the parts of the holder in blade releasing position. When the locking wedges 19 are swung outwardly, it will be understood that the plates 4 and 5 are free to be relatively rocked on the trunnions 17, so as to allow the upper edges of the plates to come close together and the clamping jaws 9 to spread, while when the locking wedges 19 are swung inwardly the upper portions of the plates 4 and 5 will be spread or moved outwardly, while the jaws 9 will be moved inwardly to clamping position. In Figures 2 and 3 I have shown a safety razor blade 21 of the Gillette type applied for use. Blades of this type are thin metal blades having opposite longitudinal cutting edges, which are devoid of a bead or reinforcement. Blades of this type may be inserted for use directly between the clamping faces 10 of the jaws 9 at the front of the holder and fitted in place so that the body of the blade will be disposed between the plates 4 and 5 and the acting edge of the blade caused to project a desired distance beyond the front edges of

the jaws. The blade may then be secured in position by swinging the wedges 19 inwardly, thereby closing the jaws 9 and forcing their clamping faces 10 into engagement with the sides of the blade, firmly clamping the latter in position. When the blade is thus applied, the device may be used for shaving like an ordinary old style razor and the blade so held may be stropped or honed or otherwise resharpened, as the projecting cutting edge will be held in proper position for stropping and honing or other resharpening actions. In stropping or honing a blade, it will be understood that the device may be manipulated over a strap or hone in a manner similar to an old style razor blade, the flanges 7 and beveled surfaces 11 in these operations serving to support and guide the holder at the proper angle conforming to the bevel of the edge of the blade. In honing a blade, after one edge has been honed, it will be understood that the blade may be reversed in the holder and the other edge honed in an obvious manner. The surfaces 11 are of such degree of bevel as to reduce down the front edges of the jaws 9 so that they will come quite close to the projecting edge of the blade, allowing the blade to be brought as closely as desired to the surface of the skin for as close a shave as may be desired by the user. In releasing a blade, it is simply necessary to swing the wedges 19 outwardly, whereupon by pressure on the upper portions of the plates 4 and 5 the jaws 9 may be spread to allow the blade to drop out or to be readily extracted.

In Figures 6 and 7 I have shown the mode of applying and holding a comparatively stiff safety razor blade 22 of the "Gem," "Eveready" or other similar type having a single longitudinal cutting edge 23 and a bead or reinforcement 24 along its opposite longitudinal edge. Blades of this type may be inserted, as shown in Figure 6, between the plates at the top of the holder, when the locking wedges 19 are released, the blade dropping down in position between the jaws 9, as shown in Figure 7, so that upon swinging the wedges 19 inwardly to closed position the jaws 9 will be closed to firmly clamp the blade. Such blades may be released and removed by reversal of the operation described. Other blades of this general type may be used in a similar manner, rendering the device adaptable for the use of any of the forms of safety razor blades now commonly employed, either by application and removal via the front or the rear of the holder as hereinbefore described.

From the foregoing description, taken in connection with the drawings, it will be seen that my invention provides a safety razor blade holder which is not only adapted for the use of all kinds of safety razor blades,

but holds the blade so that it may be employed for shaving, stropping, honing and resharpening actions like an ordinary old style razor, the convenience of which will be manifest. Also it will be seen that the invention provides a simple and inexpensive type of holder which may be readily and conveniently manipulated to clamp or release a blade and which will firmly and securely clamp the working blade in position.

The construction may be such that when the holder is not in use, no blade being held therein, the handle may be swung into the space between the jaws 9, or the construction may be such that, when the wedges 19 are swung outwardly, the handle may be swung into the space between the upper edges of the plates 4 and 5, thus adapting the device to be folded like an ordinary old style razor for convenience in storage or transportation.

Having thus fully described my invention, I claim:—

1. A safety razor blade holder comprising two loosely connected plates having instruck contacting portions on which the plates are adapted to rock on a longitudinal axis, said plates being provided with blade clamping jaws in advance of such axis, and means movable into and out of the space between the plates in rear of said axis for rocking the plates to close the jaws and for holding said jaws in clamping position.

2. A safety razor blade holder comprising two plates having offset portions forming jaws at the front thereof normally closer to each other than the body portions of the plates, said jaws having contacting instruck portions in rear of said offset portions, loose connections between the plates limiting their outward movement and cooperating with the instruck portions to adapt said plates to have rocking movement on a longitudinal axis, and spreading devices movable between the ends of the plates in rear of such axis for closing the jaws and locking them in closed position.

3. A safety razor blade holder comprising two plates having offset portions forming jaws at the front thereof normally closer to each other than the body portions of the plates, said jaws having instruck contacting portions in rear of said offset portions, loose connections between the plates limiting their outward movement and cooperating with said instruck portions to adapt said plates to have rocking movement on a longitudinal axis, and wedges pivotally mounted between the ends of the plates in rear of the instruck portions for spreading the plates in rear of said instruck portions to cause the jaws to move inwardly to clamping position, and for locking them in such position.

In testimony whereof I affix my signature.
MICHAEL CROUGH.
